SPORT PRACTICE APPARATUS

Benjamin H. Neiden, Oakland, Calif.

Application August 20, 1940, Serial No. 353,367

3 Claims. (Cl. 273—29)

This invention relates to apparatus for practising and teaching athletic sports involving the striking of a ball, as in tennis and golf.

One object of the invention is to provide apparatus for this purpose in which the ball is supported for striking by the player in the same positions in which the ball is struck in actual play. For example, in practicing tennis the ball may be supported overhead for serving and waist-high for ground strokes, etc., while in practicing golf the ball may be supported in teed-up position on the ground.

Another object of the invention is to provide apparatus for this purpose in which the ball when struck travels around in a circular path tangent to the normal line of flight of the ball.

In the drawings:

Fig. 1 is a side elevation of an apparatus particularly intended for tennis.

Fig. 2 is a front elevation thereof.

Fig. 3 is a side elevation, partly in section, of an apparatus particularly intended for golf.

Fig. 4 is a similar view of a modification of the apparatus shown in Fig. 3.

Fig. 5 is a plan view thereof.

Fig. 6 is a plan view with parts in section of the means for supporting the ball in the apparatus shown in Fig. 1.

Fig. 7 is a front elevation thereof.

The tennis apparatus will be described first. It comprises a rectangular base 10 (Figs. 1 and 2) which may be constructed of wood and which is provided with blocks 11 and 12 by means of which it is spaced from the wall 13 or other vertical part of a building to which it is attached by any suitable means, such as bolts 14 and 15.

Intermediate the wall 13 and the base 10 is disposed a clamping block 16 which may be of wood and is substantially the same width as base 10. Four bolts 17 provided with wing nuts pass through apertures in the block 16 and through two slots 18 and 19 (Fig. 2) in the base 10. A support, indicated generally at 20 (Fig. 1), is adapted to be secured in any adjusted vertical position on the base 10 by means of the clamping block and its bolts 17.

The support 20 is constructed of metal pieces secured together, as by welding. It comprises two vertical angles 21, 22 (Fig. 2) welded to two horizontal straps 23, 24. A V-shaped member 25 (Fig. 6) constructed of angle iron has its ends 26, 27 secured to vertical angles 21, 22 at the tops thereof. The member 25 projects out horizontally and at its outer end it has a portion 28 parallel to the base 10 which is apertured to re-

ceive a bolt 30. A diagonal brace 29 (Fig. 1) provides additional support for the outer end of the member 25.

The bolt 30 (Fig. 6) is held in place in the portion 28 of the member 25 by a nut 31 and a lock nut 32. The lock nut 32 is spaced from the head 33 of the bolt to expose the shank of the bolt which serves as a pivot for an S-shaped swivel 34 (Fig. 7) having a flexible, but inextensible, means, such as a cord or wire 35 attached thereto at 36.

A tennis ball 40 is attached to the end of the wire 35 at 41. A rubber tube or sheath 42 is preferably placed around the wire 35 to protect the racket 43 (Fig. 1).

The operation of the apparatus for practising tennis strokes is as follows: The base 10 is mounted on the wall 13 and the support 20 is attached to the bolts 17. In order to practise overhead strokes, such as the service and the smash, the support is raised to a position such as that shown in full lines in Figs. 1 and 2 where the ball 40 is at the desired height. Then the wing nuts on the bolts are tightened to clamp the block 16 against the base 10 to hold the support 20 firmly in place.

When the ball 40 is struck by the racket it travels around in a circle the center of which is on the axis of the bolt 30. To practise strokes at lower elevations, such as the forehand and backhand drives, the support 20 is lowered to the position indicated in broken lines in Figs. 1 and 2. The path of travel of the ball when struck is indicated by the circle 45 in Fig. 2. The circle 45 is tangent to the line 46 which would be the normal line of flight of the ball in play. If the ball is hit flat and in a line parallel to the wall 13 (Fig. 1) the ball will rotate in a vertical plane 47.

If the ball is sliced or hit on a diagonal line it will rotate in an inclined plane such as that indicated at 48. The ball whirls in this plane for some time, thus serving as a visible indication of the manner in which it was struck. This is particularly advantageous in learning the flat drive. To master this stroke on the apparatus the player strives to hit the ball so that it will rotate in the vertical plane 47.

The apparatus is readily adjustable to position the ball 40 at any elevation to accommodate players of different stature and to practise different strokes. When not in use the support 20 can be detached by removing the wing nuts of the bolts 17. The mounting blocks 11, 12 should be thick enough to prevent the bolts 17 from

disengaging from the slots 18, 19 when the support 20 is removed so that the ends of the bolts will project through the slots for again attaching the support.

The golf practice apparatus comprises a stake 53 (Fig. 3) adapted to be driven into the ground. A shaft or pin 51 is rotatable in a bore 52 in the stake and is held therein by a set screw 53 threaded through the stake and engaging in a groove 54 in the shaft. A rod 55 is rigidly secured in the shaft 51 to project horizontally from the upper end thereof. A golf ball 56 or a suitable representation thereof is rigidly secured to the outer end of the rod 55 which serves as a supporting arm therefor. The ball 56 is thus supported in teed-up position above the ground. The player practises his strokes by striking the ball 56 with a golf club 57. When the ball is struck it travels in a circle tangent to the normal line of flight of the ball, the shaft 51 rotating in the stake 53.

The apparatus shown in Figs. 4 and 5 is adapted to be attached to the floor for use indoors. For this purpose the shaft 51' is received in the bore 52' of a member 60 having a flange 61. Screws 62 passing through the flange 61 are threaded into the floor 63. The shaft 51' is retained by a set screw 53' engaging in a groove 54'. The golf ball 56' is supported on an arm 55' secured in the shaft 51'. A mat 64 is placed under the ball on the floor. When the ball 56' is struck by the club 57 it travels around in the circle 65 (Fig. 5) which is tangent to the normal line of flight 66.

Having disclosed my invention and the manner in which it is to be used, I claim:

1. An apparatus for practising tennis comprising a support, a second support, means to detachably secure said second support to said first support in a selected vertical position on said first support, a ball, and means to suspend said ball from said second support.

10 2. An apparatus for practising tennis comprising a vertical support, a horizontally-extending bracket, means to suspend a tennis ball from the outer end of said bracket for rotation in a circle when struck, and means to clamp said bracket to said support comprising a clamping member 15 adapted to engage the rear side of said support, and a plurality of bolts extending through said member and said bracket, whereby said tennis ball may be positioned for practising overhead strokes, such as the serve, or ground strokes, such 20 as the drive, by clamping said bracket at the required height above the ground on said vertical support.

3. An apparatus for practising tennis comprising a support adapted to be secured to the wall 25 of a building, said support having a plurality of spaced apart parallel slots extending vertically substantially the length of said support, a clamping block, a horizontally-extending bracket, bolts extending through said block, said slots and said 30 bracket for clamping said block and said bracket on said support, and means to suspend a tennis ball from the outer end of said bracket for rotation in a circle when struck.

BENJAMIN H. NEIDEN.
